UNITED STATES PATENT OFFICE.

LEWIS CHADWICK, OF NELSONVILLE, OHIO.

MINE-PUMP.

1,078,126.

Specification of Letters Patent. Patented Nov. 11, 1913.

Application filed December 4, 1912. Serial No. 734,932.

To all whom it may concern:

Be it known that I, LEWIS CHADWICK, a citizen of the United States of America, residing at Nelsonville, in the county of 5 Athens and State of Ohio, have invented certain new and useful Improvements in Mine-Pumps, of which the following is a specification.

This invention relates to mine pumps, and 10 contemplates the provision of an improved structure of this character more fully set forth in the following detailed description, and illustrated in the accompanying drawings, in which—

15 Figure 1 is a front elevation of a mine pump, constructed in accordance with the invention. Fig. 2 is a transverse sectional view therethrough. Fig. 3 is a longitudinal sectional view therethrough, and Fig. 4 is a 20 transverse section through the pump cylinder.

Like numerals designate corresponding parts in all of the figures of the drawing.

It is a well known fact that mine pumps 25 constructed of metal, deteriorate rapidly, by reason of the presence of acids within the water pumped from mines, and it has been heretofore proposed to construct mine pumps of wood to thereby more effectually 30 resist the action of such acids.

The present invention contemplates the provision of an improved pump of this type in which the various parts are made of acid 35 resistant material and in which the pump comprises a plurality of blocks of wood suitably secured together, and having the necessary ports and chambers formed therein.

It is a further object of the invention to 40 provide a pump of this character having a cylinder lined with glass or like acid resisting material and having glass ball valves and having separate and detachable valve seats arranged in such manner as to be readily 45 and conveniently clamped in place by the placing together of the sections of the pump.

Further objects and advantages of the invention will be set forth in the detailed 50 description which now follows.

The pump forming the subject matter of the present invention comprises a supply deck 5, a cylinder deck 6 and a discharge deck 7. The supply deck 5 is located at the 55 bottom and has a supply conduit 8 formed longitudinally therein, said conduit connect-

ing with vertical channels 9, formed partially in the supply deck 5 and partially in the cylinder deck 6. Clamped to the rear of cylinder deck 6 is a block 6' containing the cylinder. The cylinder is formed by 60 boring the block 6' longitudinally at 10 to communicate with longitudinal channels 11 and 11' formed partially in the cylinder deck and partially in the block 6'. The cylinders 10 are preferably lined with glass, porcelain or like acid resistant material indicated at 12. A plunger 13 is disposed in the cylinder and may be operated through the medium of rod 14, which passes through 65 stuffing box 15. This stuffing box comprises a gland 16 which acts to force the packing material against a washer 17 which has a seating against a shoulder 18. The block 6' is bored out at 19 to permit of the insertion 70 of the lining 12.

The intake valve comprises a wooden valve seat 20 in which a glass ball valve 21 has a seating. Ribs 22 limit the upward movement of said valve without interfering 80 with the passage of the water. The valve is provided with a horizontal flange 23 which is clamped between the sections 5 and 6 when the sections are assembled, whereby said valve is effectually held in place, but 85

is readily detachable if for any reason it is desired to remove it. In like manner the discharge valve comprises valve block 24 having a valve seat formed therein upon which a glass ball valve 25 seats, and said block is provided with a horizontal flange 26 adapted to be held between the sections 6 and 7 when the pump is assembled. The discharge valve discharges into passage 27 90 and into a discharge conduit 28 and from said discharge conduit through discharge conduits 29 and 30 formed partly in the section 6 and partly in the section 7. Secured to the outer end walls of section 6 are straps 31, and these straps at their lower 95 ends, are threaded for the reception of nuts 32 which clamp longitudinal bars 33 against the underside of section 5. Hingedly connected to the upper ends of straps 31 are rods 34, the upper ends of which are threaded for the reception of nuts 35, these nuts in 100 turn acting to force bars 36 against the top section 7, so that it will be apparent that the top and bottom sections are thereby firmly 105 bound to the central section 6. Strap 36 extends around the cylinder block 6'. Bolts 37 pass through strap 36 and into sec-

105

110

tion 6 and thus tend to press block 6' against the packing 38 to prevent leakage between the two parts 6 and 8. Strap 39 passes over the top of block 6 and around a suitable support shown at 40. A cap 41 is held in place by screws 42 and serves to close the bore 19.

It will be seen that when the plunger 13 is moved in one direction, a suction will be created in the cylinder, and channels 11 and 9, thereby raising the ball valve 21 and allowing the fluid to flow in from the port 8, but when the plunger is pushed in the opposite direction, the intake valve will close against the tendency of the water to flow outward, and thus unseat discharge valve 25 and allow the water to flow through port 28, part of it going into discharge port 30, and part in port 29. While this discharging is taking place, the suction in channel 11 caused by the forward movement of the plunger is drawing water in, and when the plunger is again moved backward, the same action is accomplished in the other channel, and thereby gives a double-acting service.

It is believed that the operation of this device will be apparent from the structure set forth. The pump comprises a cylinder with two outlet channels, said cylinder being double-acting.

While the elements shown and described are well adapted to serve the purposes for

which they are intended, it is to be understood that the invention is not limited to the precise construction set forth, but includes within its purview, such changes as may be made within the scope of the appended claim.

Having described my invention, what I claim is:

A wooden mine pump formed of three superimposed blocks, the lowermost of said blocks being channeled to form an intake passage, the intermediate one of said blocks having a pair of separated vertical channels formed therethrough, intake valves comprising valve blocks having horizontal flanges which are clamped between the lower and the intermediate sections and across said vertical channels, discharge valves comprising separate blocks having transverse flanges clamped between the intermediate and the uppermost section and across said vertical channels and the uppermost of said blocks being channeled to form a discharge passage.

In testimony whereof I affix my signature in presence of two witnesses.

LEWIS CHADWICK.
